ATTORNEY

UNITED STATES PATENT OFFICE.

ROZALIA SUTO, OF MARTINS FERRY, OHIO.

CLOSURE FOR BEDDING.

Application filed January 27, 1928. Serial No. 249,817.

This invention relates to closures for bedding, such as pillow slips, pillow cases, mattress covers, crib ticking covers, and the like.

5 The object of the invention is to provide a closure eliminating the use of buttons, snaps, and the like, so as to provide a comparatively smooth surface.

A further object of the invention is to provide an improved closure of novel construction and arrangement of parts hereinafter more fully described, claimed and illustrated in the accompanying drawing.

15 Fig. 1 is a perspective view of a pillow case embodying my improved closure.

Fig. 2 is another form of my improved closure in strip form somewhat enlarged, adapted to be attached or secured to bedding, or the like.

20 Fig. 3 is a detail fragmentary view of my improved closure illustrating in particular the method or manner of lacing same.

Fig. 4 is a sectional view, as though taken on the line 4—4 of Fig. 3, but disclosing a 25 modified form of the invention.

Fig. 5 is a fragmentary face view looking in the direction of the line 5—5 of Fig. 4.

As here embodied my improved closure embodies knitted or crocheted members 10 and 11, formed in scallops, or somewhat curved form and secured as at 15 and 16, to the opposite edges 12 and 13, of the opening, or elongated slot formed in the pillow case 14, which is provided to permit the pillow to be 30 removed from the said case. The said crocheted members 10 and 11 are secured to the opposite edges 12 and 13, at any desired equal distances. The lacing member 17, or tape, is inserted through the loop elements of the said crocheted members 10 and 11, backwards and forwards progressively, and extends the entire length of the said crocheted members from one end thereof to the other end of the above mentioned opening formed 35 in the said pillow case 14. The above described construction is such as will permit the lacing 17, when pulled taut to enclose the said opening.

In Fig. 2 of the accompanying drawing, I 50 have shown a strip 18, to which the above described crocheted members 10 and 11 are secured or attached in the above described manner, the said strip 18 being secured to any desired cover for bedding at the opening formed therein, which will permit the above men-

tioned lacing 17 to be inserted therein, as above set forth. The above described construction is such as will permit my improved closure to be marketed as a commercial article and readily applied to any desired cover of 60 the class described and above set forth.

Figs. 4 and 5 disclose the strips 18 formed with longitudinal folds 19 so that when the material is stretched to open these folds, the size of the pillow casing to which the strips 65 are secured will be increased to accommodate a slightly different sized pillow. A plurality of spaced triangular pieces of cloth 20 are stitched to the fold and other triangular pieces 21 are stitched to the material below 70 the fold and positioned intermediate of the pieces 20. Each of the triangular pieces have loops 22 secured to the tops or bottoms so as to be in a horizontal line. Strings 23 are laced through the loops to normally hold the 75 folds 19 in folded condition. Since all of the loops are in a horizontal line, the strings 23 may be laced in a straight line, saving time in lacing and requiring less string than if the string were zig-zagged up and down. 80

While I have above described the preferred form, construction and arrangement of the several elements employed, it will be understood that the device is nevertheless, susceptible of considerable modification therein, 85 and I therefore reserve the privilege of resorting to all such changes as may be fairly embodied within the spirit and scope of the invention as claimed.

Having thus described my invention, what 90 I claim as new and desire to protect by Letters Patent of the United States is as follows:

A pillow casing having an opening therein through which a pillow is adapted to be inserted, and lacing means for closing said opening, parts of the casing opposite said opening being folded upon themselves, a plurality of spaced triangular pieces of material attached to the folded portions of the casing and other similar pieces of material 100 oppositely directed and positioned between the said pieces and attached to the material adjacent the fold and provided with attached loops, and a tensioning device passing through all of said loops for adjusting the 105 size of the casing.

In testimony whereof I have affixed my signature.

ROZALIA SUTO.
